United States Patent Office

Des. 209,101
Patented Oct. 31, 1967

209,101

BOTTLE

Charles E. Finsilver, Hartdale, N.Y., assignor to Lever Brothers Company, New York, N.Y., a corporation of Maine

Filed Aug. 29, 1966, Ser. No. 3,623

Term of patent 14 years

(Cl. D58—7)

FIG.1.

FIG.2.

FIG.3.

FIG.4.

FIG.5.

FIGURE 1 is a front elevational view of a bottle, showing my new design;

FIGURE 2 is a rear elevational view thereof;

FIGURE 3 is a sectional view thereof taken on line 3—3 of FIGURE 1;

FIGURE 4 is a top plan view thereof; and

FIGURE 5 is a bottom plan view thereof.

This is a continuation-in-part of my U.S. application Ser. No. D.1,910 filed Apr. 18, 1966, and now abandoned.

I claim:

The ornamental design for a bottle, as shown and described.
